Inventor
Frank L. Dyer

UNITED STATES PATENT OFFICE.

FRANK L. DYER, OF MONTCLAIR, NEW JERSEY.

MAGNETIC RECORDER.

Application filed February 16, 1921. Serial No. 445,416.

To all whom it may concern:

Be it known that I, FRANK L. DYER, a citizen of the United States, and residing at Montclair, county of Essex, State of New Jersey (P. O. address 16 Rockledge Road, Montclair, N. J.), have invented new and useful Improvements in Magnetic Recorders, of which the following is a full, clear, and exact description.

10 My invention relates to improvements in magnetic recorders for making sound records by operating a cutting stylus by means of telephonic currents to thereby form in a solid material a groove having vertical or 15 lateral variations, corresponding to sounds; and from which master record duplicate copies in hard material may be made by well-known processes. Preferably the telephonic currents are amplified by means of one or 20 more amplifiers, as disclosed in application of Vreeland and Dyer, filed March 14, 1919, Serial No. 282,610, to thus provide currents of substantial energy and by means of which a sound groove of substantial amplitude and 25 of great accuracy may be produced.

My improved magnetic recorder provides the following features:

1. A polarized recorder is used by which the movements of the stylus in both directions will be positively effected. With a non-polarized device, the movement in one direction is effected magnetically, the movement in the opposite direction being effected by means of a spring, and in consequence the recording is not accurate and the stylus is not under accurate and delicate control.

2. The stylus is carried by a reed or tongue which is substantially aperiodic and hence is substantially non-resonant.

3. Provision is made in a magnetic recorder for permitting the stylus to lightly engage the recording material with sufficient pressure for the desired cut, and at the same time having the desired "floating" effect, so as to be unaffected by warping or other surface irregularities of the recording material. At the same time provision is made for proper adjustment of the reed or tongue relatively to the actuating magnet or magnets as to preserve the desired relationship between them.

4. Provision is made for determining with accuracy the desired location of the armature between the magnet poles to secure

proper, uniform and equal operation by the two magnets.

5. I mount the cutting stylus on or near the forward end of the reed or tongue whereby under the relatively high recording speed the shavings will be thrown upwards and away from the vibrating elements. It is especially important that no mechanical obstruction shall lodge in the very narrow space in which the armature vibrates. Preferably provision is made by vacuum to cleanly remove all shavings as fast as formed from the neighborhood of the vibrating parts.

My object generally stated is to provide a magnetic recorder having the features of construction above referred to, as well as others to be more fully hereinafter described.

In the drawing:

Fig. 1 is a side-view of my improved magnetic recorder, showing its operation in making a talking machine record.

Fig. 2 an enlarged front elevation, partly in section, showing the magnets and allied parts, and illustrating the determining device for centering the reed or tongue.

Fig. 3, a side view on the same scale as Fig. 2, partly in section, showing the vacuum pipe in position; and

Fig. 4, a sectional view on the line 4—4 of Fig. 3.

In all of the above views corresponding parts are represented by the same numerals.

The blank 1 of suitable recording material is carried upon a rotating turn-table 2, and the cutting stylus 3 engages the blank at or close to its diameter. The turn-table is rotated, and at the same time relative horizontal movement takes place between the blank and the cutting stylus so as to cut a spiral groove in the blank. In the drawing this relative movement takes place by reason of the fact that the turn-table moves longitudinally with respect to the cutting tool. For this purpose the turn-table is mounted in a frame 4 and is rotated by a suitable motor or other driven or driving means located within the casing 5. The frame 4 is mounted upon ways 6, 6 and is fed horizontally by any usual mechanism. The ways 6, 6, are in turn formed as part of the heavy supporting bed 7.

The recording mechanism is supported by a bracket 8, secured to the bed 7 and formed

with a head 9, which is secured to a slide 10. The slide 10 is adjustable vertically by means of an adjusting screw 11. Mounted at the lower end of the slide 10 is a yoke 12, capable of slight horizontal adjustment therein. This adjustment is effected in any suitable way, as by an adjusting screw 13, mounted within the lower part of the slide 10 and engaging a lug 14 on the yoke 12, as shown in Fig. 2. Any appropriate mechanism may be employed for securing the horizontal adjustment of the yoke, that shown being merely for the purpose of illustration.

15 The yoke 12 carries two coils 15, 15, magnetizing the two poles 16, 16, which are extended inwardly as shown in Fig. 2, and form a very narrow gap between them. In Fig. 2 this gap is shown as greatly exaggerated for the purpose of clearness. The vibration of the armature between the poles is of the order of one or two thousandths of an inch, and hence the free space between the armature and the pole faces is very 25 slight. The slide 10, yoke 12 and poles 16 are all formed of iron or other magnetic material. Extending from the lower end of the slide 10 is a permanent magnet 17 having a down turned leg, as shown, and carrying brackets 18 in which are pivots 19, 19 for a rock shaft 20. This rock shaft is provided with an enlarged hub 21 working within a slot in the vertical leg of the magnet 7. By locating the shaft 20 and hub 21 35 below the vertical leg of the magnet, the magnetic pull will neutralize the weight on the pivots 19 to thus reduce friction. The hub 21 carries the tongue or reed 22, whose forward end is enlarged to form an armature 40 23. Preferably the armature and reed are integral, but at least the armature should be made magnetic. By reducing the thickness of the armature at the reed portion 22, the device will be substantially aperiodic 45 and hence non-resonant. The stiffness of the reed is sufficient to normally maintain the armature in its desired central position between the two poles 16, 16.

The cutting stylus 3 is carried by and 50 vibrates with the armature being located at the end of the armature and facing forwards so that any shavings will be deflected upwards and out of the way of the rotating parts. The ordinary cutting speeds used in 55 making talking machine records are such as to cause the shavings to be thus thrown upwards as a practically continuous stream. It is highly important that no shavings should lodge within the narrow space in 60 which the armature vibrates and therefore I prefer to use a vacuum pipe 24 to draw the shavings away and remove them clear of the apparatus. The lower end of the 65 vacuum pipe 24 is removably carried within guides 25 (see Fig. 4) secured to a plate 26,

depending from the yoke 12. This plate is formed with an index 27 located immediately over the armature 23, and the armature is formed with a central line 28, which may be brought into register with the index 27 by means of the adjusting screw 13, as will be understood. In this way the armature may be accurately adjusted midway between the two poles 16, 16 and after adjustment the vacuum pipe will be put in 75 place.

The weight of the armature 23 and cutting tool 3 may be made sufficient to cause the stylus to engage to the correct depth in the recording material, but preferably I 80 employ a spring 29 to supplement this weight, which spring is adjusted by a screw 30 so that the cutting depth can in this way be accurately regulated. It is preferable to have the cutting depth thus controlled by spring action rather than by depending upon the weight of the parts so as to thus prevent inertia from interfering with the operation. The cutting stylus can be elevated from the blank in any suitable way, as for example, by a lever 31 connected to the hub 21 and engaged by a lever 32, operated by a finger piece 33. By providing for vertical adjustment of the slide 10 the magnetic poles 16 can be kept always in 85 proper relation to the armature 23, any vertical movements of the armature being 90 of course relatively inconsiderable.

It will not be necessary to describe in detail the electric connections since the operation of the polarized magnets is the same as with the well-known telegraph polarized relays.

Having now described my invention, what I claim as new therein, and desire to secure by Letter Patent, is as follows:

1. In a magnetic recorder, the combination with polarized magnets, an aperiodic armature operated thereby and freely movable in a plane parallel to the polar faces, and a cutting tool carried by the armature, substantially as set forth.

2. In a magnetic recorder, the combination with a magnet, an armature actuated thereby, said armature being vibratable towards and from the polar faces and being freely movable in a plane parallel to the polar face, and a cutting stylus carried by the armature, substantially as set forth.

3. In a magnetic recorder, the combination with a magnet, of an armature vibratable towards and from the polar face and freely movable in a plane parallel to the polar face, a cutting stylus carried by the armature, and means for adjusting the magnet in a plane parallel with its polar face, substantially as set forth.

4. In a magnetic recorder, the combination of polarized magnets having opposed polar faces and influenced by telephone cur-

- rents, an armature located between said polar faces and actuated by said magnets, and a cutting stylus carried by the armature and so located as to cause shavings to be deflected away from the gap between the polar faces, substantially as set forth.
5. In a magnetic recorder, the combination with a magnet, an armature vibratable towards and from its polar face, a cutting stylus carried by the armature and located to cause shavings to be directed away from the magnet, and a suction pipe removably carried by the magnet and into which the shavings are directed, substantially as set forth.
10. In a magnetic recorder, the combination with a magnet, a pivoted armature movable freely in a plane parallel with the polar face and vibrating towards and away from the polar face, a cutting stylus carried by the armature, and means for regulating the depth of cut of the cutting stylus, substantially as set forth.
15. In a magnetic recorder, the combination with a magnet, a pivoted armature movable freely in a plane parallel with the polar face and vibrating towards and away from the polar face, a cutting stylus carried by the armature, and an adjustable spring for regulating the depth of cut of the cutting stylus, substantially as set forth.
20. In a recording apparatus the combination of polarized magnets, an armature located between the magnetic poles, means for adjusting the magnets with respect to the armature to locate the armature centrally between the poles, and a cutting stylus carried by the armature, substantially as set forth.
25. In a magnetic recorder the combination of polarized magnets, an armature located between the magnetic poles and pivoted so as to move freely in a plane parallel to the polar faces, said armature being vibrated towards and away from the polar faces and a cutting stylus carried by the armature, substantially as set forth.
30. In a recording apparatus the combination of polarized magnets, a pivoted armature located between the polar faces and movable freely in a plane parallel to the polar faces, means for adjusting the magnets in a plane parallel to their polar faces, means for adjusting the position of the armature with respect to the polar faces and a cutting stylus carried by said armature, substantially as set forth.
35. In a magnetic recorder, the combination of polarized magnets, a permanent magnet cooperating therewith, an armature pivoted upon the permanent magnet to move freely in a plane parallel to the polar faces of the polarized magnets and a cutting stylus carried by said armature, substantially as set forth.
40. In a magnetic recorder the combination of polarized magnets, a permanent magnet cooperating therewith, a pivoted rock shaft, the weight of which is neutralized by the magnetic pull, an armature carried by the shaft and movable freely in a plane parallel to the polar faces of the polarized magnets, and a cutting stylus carried by said armature, substantially as set forth.
45. In a magnetic recorder, the combination of a magnet, an armature movable freely in a plane parallel to the polar faces and vibratable towards and from the polar face, a cutting stylus carried by the armature, and means for manually moving the armature in a plane parallel to the polar face, substantially as set forth.
50. In a magnetic recorder, the combination of polarized magnets, of an armature located between the polar faces and freely movable in a plane parallel with the polar faces, a cutting stylus carried by the armature, and means for adjusting the magnets both vertically and horizontally, substantially as set forth.
55. In a magnetic recorder the combination of polarized magnets, a pivoted armature located between the polar faces and movable freely in a plane parallel to the polar faces, means for adjusting the magnets in a plane parallel to their polar faces, means for adjusting the position of the armature with respect to the polar faces and a cutting stylus carried by said armature, substantially as set forth.
60. In a magnetic recorder, the combination of polarized magnets, a permanent magnet cooperating therewith, an armature pivoted upon the permanent magnet to move freely in a plane parallel to the polar faces of the polarized magnets and a cutting stylus carried by said armature, substantially as set forth.
65. In a magnetic recorder the combination of polarized magnets, a permanent magnet cooperating therewith, a pivoted rock shaft, the weight of which is neutralized by the magnetic pull, an armature carried by the shaft and movable freely in a plane parallel to the polar faces of the polarized magnets, and a cutting stylus carried by said armature, substantially as set forth.
70. In a magnetic recorder, the combination of polarized magnets, a permanent magnet cooperating therewith, a pivoted rock shaft, the weight of which is neutralized by the magnetic pull, an armature carried by the shaft and movable freely in a plane parallel to the polar faces of the polarized magnets, and a cutting stylus carried by said armature, substantially as set forth.
75. In a magnetic recorder, the combination of a magnet, an armature movable freely in a plane parallel to the polar faces and vibratable towards and from the polar face, a cutting stylus carried by the armature, and means for manually moving the armature in a plane parallel to the polar face, substantially as set forth.
80. In a magnetic recorder, the combination of polarized magnets, of an armature located between the polar faces and freely movable in a plane parallel with the polar faces, a cutting stylus carried by the armature, and means for adjusting the magnets both vertically and horizontally, substantially as set forth.
85. In a magnetic recorder, the combination of polarized magnets, a pivoted armature located between the polar faces and movable freely in a plane parallel to the polar faces, a cutting stylus carried by the armature, and means for adjusting the magnets both vertically and horizontally, substantially as set forth.
90. In a magnetic recorder the combination of polarized magnets, a permanent magnet cooperating therewith, an armature pivoted upon the permanent magnet to move freely in a plane parallel to the polar faces of the polarized magnets and a cutting stylus carried by said armature, substantially as set forth.
95. In a magnetic recorder the combination of polarized magnets, a pivoted armature located between the polar faces and movable freely in a plane parallel to the polar faces, means for adjusting the magnets in a plane parallel to their polar faces, means for adjusting the position of the armature with respect to the polar faces and a cutting stylus carried by said armature, substantially as set forth.

This specification signed and witnessed
this 14th day of February, 1921.

FRANK L. DYER.
